*Primary Examiner—A. Hugo Word**Assistant Examiner—Robin V. Taylor
Attorney, Agent, or Firm—Oldham & Oldham Co., L.P.A.*[57] **CLAIM**

The ornamental design for an invalid lifter, as shown and described.

DESCRIPTION

FIG. 1 is a perspective view of the design;

FIG. 2 is a top plan view of the design as shown in FIG. 1;

FIG. 3 is a bottom plan view of the design as shown in FIG. 1;

FIG. 4 is a front elevational view of the design as shown in FIG. 1;

FIG. 5 is a left side elevational view of the design as shown in FIG. 1;

FIG. 6 is a right side elevational view of the design as shown in FIG. 1;

FIG. 7 is a rear elevational view of the design as shown in FIG. 1;

FIG. 8 is a side elevation view of the invention showing an invalidated person seated on a chair just prior to using the invention, the broken line showing of the human form is for illustrative purposes only and forms no part of the claimed design; and,

FIG. 9 is a side elevation view of the invention showing the invalidated person using the invention to rise from a sitting position, the broken line showing of the human form is for illustrative purposes only and forms no part of the claimed design.
